UNITED STATES PATENT OFFICE.

BENJAMIN HARRISON CORT, OF BROCKTON, MASSACHUSETTS, ASSIGNOR TO STACY ADAMS COMPANY, OF BROCKTON, MASSACHUSETTS, A CORPORATION OF MASSACHUSETTS.

SHOE.

Application filed April 26, 1926. Serial No. 104,563.

This invention relates to shoes and shoe soles, more particularly to innersoles and has for its object to increase the comfort of the shoe to the wearer by providing a yielding support for the foot conforming closely to its surface and providing supports for its metatarsal, transverse and longitudinal arches.

To this end the sole or innersole is formed with a pair of superposed laminations extending from a line somewhat forwardly of the shank at the forepart of the shoe to the heel end and between these laminations is inserted a cushion member which may well be formed of a layer of soft sponge rubber. Preferably the cushion member is cemented or otherwise fixed to the upper lamination, but is unattached to the lower lamination except at its extreme forward end so that the upper lamination and cushion member are free to yield and to conform to the foot unhampered by attachment to the shoe upper or outersole, which, in the case of an innersole, are both fixed to the lower lamination. The forward end of the cushion member is skived to a thin edge along a curved outline conforming somewhat closely to the curve of the metatarsal arch so that in the completed innersole a rounded projection is formed on its upper face between its side edges to furnish a proper support for this arch.

For a more complete understanding of this invention, reference may be had to the accompanying drawings in which

Figure 1 is a perspective of an innersole blank cut to receive the cushion member.

Figure 2 is a perspective of the cushion member.

Figure 3 is a top plan of the blank and cushion member assembled.

Figure 4 is a longitudinal section through a welt shoe showing an innersole constructed according to this invention, the bones of a foot being shown.

Referring to these drawings, at 1 is shown an inner sole blank which is first split from its heel end to form lower and upper laminations 2 and 3. This split portion extends forwardly of the shank and its central portion is extended further than its side portions, as shown by the dotted line at 4, or it may be split substantially uniformly as shown by the dotted line 5 and later cemented together over that portion between the lines 4 and 5, this being done for ease in manufacture.

In place of splitting the innersole, it might

be formed with less advantage from two sole shaped blanks cemented together over their forepart portion to substantially the line indicated at 4.

Preferably also the central portion of the upper layer adjacent to the concave central portion of the line 4 is perforated at intervals. This not only acts as a ventilating means for the sole, but also serves to weaken the central portion of the upper lamination so that it may be distorted upwardly as will later appear.

At 10 (Figure 2) is indicated a cushion member formed of a sheet of soft sponge rubber. This in practice may be approximately a quarter of an inch thick when uncomressed. The forward end of this cushion member is skived to a thin edge as shown at 11 and is given a contour substantially that of the dotted line 4 of Figure 1. The remainder of the outline of the cushion member conforms to the outline of the sole extending to the heel end. This cushion member is inserted between the laminations 2 and 3 and is preferably cemented to the top lamination 3 only, being entirely free from the lamination 2, except at its extreme forward end where it may be cemented thereto or by the attachment of the upper lamination to the lower at the forward end of the split portion.

When the sole is in the shoe this cushion member 10 acts to press upwardly the material of the upper lamination to form a rounded projection at the forward end of the cushion member which acts to support the metatarsal arch of the foot. The cushion material being soft permits the upper lamination to yield to the pressure of the foot, thus causing it to conform automatically to the longitudinal arch and the transverse arch along the cuneiform bones.

The position of the arches of the foot with relation to the cushion portion of the sole is indicated in Figures 3 and 4 where the phalanges are indicated at 20 and the metatarsals 21. It will be seen that the forward protuberance of the sole at the forward end of the cushion member comes beneath the metatarsal bones and conforms, more particularly when the weight of the wearer comes thereon, to the metatarsal arch, while the portion of the sole to the rear of this arch is depressed where the greatest pressure is exerted thereon so that it conforms automatically to the foot throughout the shank and heel portion.

As shown the heel end of the upper-lamination is also perforated as shown at 25 in Figure 1, sometimes this being found desirable.

When this innersole is used in a welt or 5 McKay shoe, or the like, its forward portion is attached to the outer sole and other parts of the shoe in the usual manner, while where the laminations occur the lower lamination only is attached. For example, in a welt 10 shoe, as shown in Figure 4, the welt at 30 is attached to the forward portion of the innersole member while at the rear portion the lower lamination only is attached to the welt, the upper lamination and the cushion member 15 being free to slide on the lower lamination to conform to the motion of the foot in walking. It is, of course, evident that instead of forming this sole member as the innersole of a welt or McKay shoe, it might be 20 formed as a separate sole member to be inserted in the finished shoe, as for example, with a turn shoe in which there is but a single sole fixed to the upper.

Having thus described an embodiment of 25 this invention it should be evident to those skilled in the art that many other changes and modifications might be made therein without departing from its spirit or scope as defined by the appended claims.

30 I claim:

1. A shoe sole comprising a pair of laminations extending rearwardly from the forepart, and a cushion member interposed between said laminations and tapered at its for-

ward end, said cushion member extending 35 from the heel end and further forwardly at its central portion than at its side edges to cause the upper face of said sole to present a rounded portion forming a metatarsal arch support.

2. A shoe sole comprising a pair of laminations extending rearwardly from the forepart, and a cushion member interposed between said laminations and extending from the heel end of said sole forwardly and tapered at its forward end, said cushion member extending further forwardly at its central portion than at its side edges to cause the upper face of said sole to present a rounded portion forming a metatarsal arch support, 40 45 the upper lamination being perforated over said upwardly rounded portion.

3. A shoe sole comprising a pair of laminations extending rearwardly from the forepart, and a cushion member interposed between said laminations and extending forwardly from the heel end of said sole, said member being tapered at its forward end and being fixed to one of said laminations only and extending further forwardly at its central portion than at its side edges to cause the upper face of said sole to present a rounded portion forming a metatarsal arch support.

In testimony whereof I have affixed my 55 signature

BENJAMIN HARRISON CORT.
